UNITED STATES PATENT OFFICE

2,610,577

SCREEN PRINTING MACHINE

Clemens Anton Heintges, Uddevalla, Sweden, assignor to Aktiebolaget Teximpex, Gothenburg, Sweden, a corporation of Sweden

Application October 3, 1949, Serial No. 119,265
In Sweden October 5, 1948

5 Claims. (CL. 101—115)

1

The present invention refers to so-called screen printing machines, wherein the stencils are arranged in carriages or the like, which are stored above each other in one or more magazines adapted to be raised and lowered, and the arrangement in consideration is principally distinguished by the feature that the magazine is adapted to be moved in the vertical direction with the aid of an electric motor, for example, means being also provided to bring about a stepwise displacement at least at the movement of the magazine in one direction so that the carriages placed on top of each other are brought to a standstill one after the other on a level with a track or the like for the carriages arranged transversely over a printing table.

The accompanying drawings illustrate a few examples of embodiment of the invention. Fig. 1 is a perspective view of a magazine arranged in accordance with the invention. Fig. 2 shows a detail of the arrangement according to Fig. 1 in elevation. Fig. 3 is a diagrammatic representation of a locking device comprised in the arrangement according to Fig. 1. Figs. 4-6 show a further embodiment of the invention in various projections. Fig. 7 with its continuation Fig. 7a is an elevation of a printing table associated with the arrangement shown in Figs. 4-6. Fig. 8 with its continuation Fig. 8a is a plan view of the printing table according to Fig. 7.

In Fig. 1, numeral 1 designates a frame, and arranged in this frame is a magazine 2 adapted to be raised and lowered as a lift-cage, said magazine being guided by means of guides 3 equipped with a plurality of pairs of rails or the like 4 arranged above each other, carriages 5 being displaceably arranged on said rails. The carriages 5 have stencils arranged thereon in known manner, each of said stencils corresponding to a certain color. In the example shown, the magazine contains eight carriages, which thus renders printing possible with eight colors.

Secured to the upper borders of the magazine 2 are ropes 6 running over guide pulleys 7, 8 and carrying counterweights 9, one on each side of the magazine. Provided alongside of two opposed sides of the magazine are vertical racks 10 cooperating with gear wheels, which latter are not shown here, and which are driven over a shaft 11 and chains 12 by means of an electric motor 13, a suitable gearing 14 being provided between the motor 13 and the shaft 11. Fig. 1 also diagrammatically indicates a printing table 15 with rails 16, on which the carriages 5 are intended to run when withdrawn out of the magazine.

2

In the embodiment according to Fig. 1, the counterweights 9 are somewhat lighter than the filled magazine 2 which consequently tends to descend. On account thereof there is provided a locking device arranged in accordance with Figs. 2 and 3.

The locking device proper is shown diagrammatically in Fig. 3 and comprises a locking member 17 engaging the lower sides of the rails 4 in the magazine. The locking member 17 is retained in locking position by a spring 18 and may be withdrawn from this position with the aid of an electromagnet 19. In the example shown, the locking device is enclosed within a casing 20.

As will appear from Fig. 2, the locking device 20 is connected by means of wires 21 to a contact device 22, which for the sake of simplicity is shown in the form of two contact members 23 and 24, of which the latter is resilient so as normally to be kept in its open position. When the carriage 5 is moved into the magazine from the table 15, the left end of the carriage in the figure will strike against the contact member 24, so that the circuit is closed and the locking device 20 disengaged. The magazine 2 will thus fall down by its own weight. However, the carriages 5 arranged on top of each other are guided in the horizontal direction by a vertical rail 25 which is approximately on a level with the table 15 has an outwardly curved portion 26 so that the contact member 24 becomes accessible to the moved-in carriage. Now, when the magazine descends by reason of the withdrawal of the locking member 17, said carriage will be moved back for a distance so as to take a normal position in alignment with the other carriages, the contact between the members 23 and 24 being thus interrupted. Hereby the locking member 17 will again be moved into its locking position, so that the magazine will be stopped by the engagement of the locking member 17 with the lower side of the rail 4 next above. The coloring of the printing material with the color in question having been finished, the cycle of operations will be repeated when the carriage running on said rail is moved into the magazine. The magazine will thus be moved downwardly in a stepwise fashion.

When all of the stencils in the magazine have been used and the magazine takes its lowermost position, a contact for the motor 13 is actuated, so that the motor will raise the magazine into its initial position topmost in the frame 1. In the example shown, the locking member 17 is bevelled off on the lower side thereof, so as to be automatically displaced by the rails 4 when the magazine moves upwardly, but it is evidently possible

to keep the circuit through the electromagnet 19 closed by means of a special contact device so that the locking plunger will be kept away all the time.

The starting of the motor 13 may be effected automatically at the lowering of the magazine to its bottom position, a contact device being thus actuated, which also breaks the current when the magazine reaches its topmost position, but it is also conceivable to make use of a manually operable switch.

In the embodiment according to Figs. 4-6 there are two magazines 52 located on both sides of a printing table 65, which is diagrammatically indicated in Fig. 4. In this case, the two magazines are interconnected by means of ropes 56, in a manner such that one of the magazines is raised, when the other one is lowered. The ropes 56 are lengthened, approximately at the middle thereof, by means of a driving chain 89 running over guide rollers 81 and a pinion 82, which is driven over a gearing 83, not shown in detail, by means of an electric motor 84 with the aid of a belt drive 85. A contact device pertaining to the motor is also combined with the gearing 83, said contact device being operated by means of a lever 86 and adapted upon closing of the circuit to be interrupted again, when the magazines have moved for a distance corresponding to that between adjacent rails 54. This interruption may be effected, for instance, through the actuation of a cam or the like arranged on a shaft comprised in the gearing, said shaft performing one revolution at said displacement of the magazines.

In the arrangement according to Figs. 4-6, each magazine contains eight carriages, which renders printing with sixteen colors possible. For each displacement of the magazines, printing may be effected with two colors, that is to say with one stencil from each magazine.

Fig. 7-7a show a printing table adapted to be placed between the two magazines in Figs. 4-6. The printing base is designated by 65, and running over this base is an endless rubber web 90, which may be given the desired tension by means of displaceable guide rollers 91. At one end of the printing base 65 is provided a diagrammatically indicated receptacle 92 having a roller 93 arranged therein, which is in contact with a further roller 94, which in turn bears on the rubber web 90. The receptacle 92 contains an adhesive, which is applied by the rollers 93 and 94 in a suitable quantity onto the surface of the rubber web 90, so that the fabric unwound from a roll 95 and to be printed upon will be safely secured to the web.

The rubber web 90 is adapted to be fed in a stepwise fashion with the aid of a diagrammatically indicated electric motor 96, from which the power is transmitted over a suitable gearing onto a guide roller 97. Coupled to this roller is a device comprising a rack 98 and a friction coupling contrivance, not shown in detail here, for automatically limiting the feeding length of the textile material.

As indicated by chain-dotted lines, the printed fabric 100 is carried from the printing table into a diagrammatically indicated drying apparatus 101, in order then to be wound onto a roll or to be folded in the ordinary manner.

Extending transversely over the printing base 65 are two rails 66 for the carriages 54. These rails 66 are supported by vertically displaceable bars 102, which are adapted to be raised and lowered by means of four cams 103 arranged in

pairs on two shafts 104. The shafts 104 are interconnected by means of a chain 105. One of the shafts 104 carries a sprocket wheel for a chain 106 connecting the shaft with an operating lever 107.

Arranged on the printing base are two pins 108 engaging adjusted apertures or the like in the carriages 54, so that all of the carriages are brought into exactly the same position when lowered toward the printing base 65. In Fig. 7, 118 denotes a lever for the disengagement of the motor 96 after the rubber web 90 has been fed forward for the intended distance.

Figs. 8-8a represent a plan view of the printing table according to Fig. 7, where the various details have been designated by the same reference numerals as in the latter figure. Fig. 8 also shows a motor-driven device for moving the carriages out of and into the magazines. In the examples shown, the displacement of the carriages is effected with the aid of pressure medium plungers arranged in cylinders 110. These cylinders have a length corresponding at least to the movement of the carriages 5, and secured to the ends of the plunger rods 111 of the same length are carriers 112 running on a rail 113. As will be seen from the figure, the carriages are provided with projections 114 engaging vertical slots in the carriers 112, so that the projections 114 on the carriages disposed on top of each other in the magazines may be moved into and out of said slot, when the carriers 112 are in their positions of rest.

Each cylinder 110 is provided with two pipe connections 115 for a pressure medium, and these pipe conduits may be alternately brought into communication with pressure and discharge conduits by means of a suitable valve device for the purpose of effecting a displacement of the plunger rods 111.

Through the means described hereinbefore, the manual work in textile printing of the type in consideration may be limited to a minimum, inasmuch as the displacement of the magazines as well as the movement of the carriages and the feeding of the fabric are effected by mechanical means. All operating levers and the like may be located immediately adjacent to the printer's platform, which in Fig. 7 is designated by 116, the printing machine in consideration becoming thus very convenient to handle.

Even if the arrangement according to the invention primarily refers to the printing of textiles, it is obviously also suited for printing of paper and the like, such as wall-paper. In the embodiments described, the displacement of the magazines is effected with the aid of an electric motor, but it is also conceivable to make use of other motors such as hydraulic or pneumatic motors. Analogously, the pressure medium operated plungers for the displacement of the carriages may be replaced, for instance, by electric motors with ropes, racks or the like for the transmission of the movement to the carriages. The machine may also be provided with mechanical squeegeeing means.

What I claim is:

1. A screen printing machine comprising an upstanding frame, a magazine vertically guided in said frame including a plurality of vertically spaced pairs of horizontally aligned guide rails, a carriage for a screen printing frame mounted on each pair of guide rails in said magazine and adapted to be withdrawn therefrom and returned thereto individually along a horizontal path, a

printing table adjacent said upstanding frame and including spaced guide rails positioned for end to end alignment with the respective pairs of guide rails in said magazine to receive the carriages from said magazine in succession upon vertical shifting of said magazine to positions to align the guide rails thereof with the guide rails on said printing table, means including an electric motor in driving engagement with said magazine and a counterweight at least partially counterbalancing the loaded weight thereof for effecting vertical movement thereof in said frame and the step by step successive alignment of the respective pairs of guide rails thereof with the guide rails on said printing table in succession, a retractable latch member engageable with spaced abutments on said magazine for locking the same in positions of alignment of the guide rails thereof with the guide rails on said printing table and means for retracting said latch means actuated by said carriages upon return thereof to stored position in said magazine after each printing operation to release said magazine for movement to bring the next pair of guide rails into position in alignment with said guide rails on said table.

2. A screen printing machine according to claim 1 including a vertically disposed guide rail carried by said frame and engaged by said carriages in said magazine to limit the movement thereof into the carriage, said guide rail having a recessed portion opposite the position of a carriage when in position of alignment with the guide rails on said table to permit return movement of a carriage past the normal position occupied by the remainder of the carriages in the magazine upon return thereof from the printing position, and entry into said recessed portion, a control switch actuated by a carriage entering said recessed portion of said guide rail for retracting said latch means to release said magazine, and a cam surface on said guide rail for shifting said last mentioned carriage to normal position to disengage said switch upon movement of said magazine.

3. A screen printing machine comprising two upstanding frames, a magazine vertically guided in each frame, each magazine including a plurality of vertically spaced pairs of horizontally aligned guide rails, a carriage for a screen printing frame mounted on each pair of guide rails in each magazine and adapted to be withdrawn therefrom and returned thereto individually along a horizontal path, a printing table between said frames, said table including spaced guide rails positioned for end to end alignment with the respective pairs of guide rails in said magazines to receive the carriages from said magazines in succession upon vertical shifting of said magazines to positions to align the guide rails thereof with the guide rails on said printing table, flexible interconnected suspension means

for said magazines whereby one is elevated when the other is lowered and each constitutes a counterweight for counterbalancing the other and means including an electric motor in driving engagement with said magazines for effecting vertical movement thereof in said frames and the step by step successive alignment of the respective pairs of guide rails thereof with the guide rails on said printing table in succession.

4. A screen printing machine comprising an upstanding frame, a magazine vertically guided in said frame including a plurality of vertically spaced pairs of horizontally aligned guide rails, a carriage for a screen printing frame mounted on each pair of guide rails in said magazine and adapted to be withdrawn therefrom and returned thereto individually along a horizontal path, a printing table adjacent said upstanding frame and including spaced guide rails positioned for end to end alignment with the respective pairs of guide rails in said magazine to receive the carriages from said magazine in succession upon vertical shifting of said magazine to positions to align the guide rails thereof with the guide rails on said printing table, means including an electric motor in driving engagement with said magazine and a counterweight at least partially counterbalancing the loaded weight thereof for effecting vertical movement thereof in said frame and the step by step successive alignment of the respective pairs of guide rails thereof with the guide rails on said printing table in succession, a guide bar extending across said printing table adjacent and parallel to one of the carriage receiving guide rails thereof, a motor actuated reciprocating carrier slidable on said guide bar, and interengaging coupling means on said carriages and said reciprocating carrier engageable upon movement of a carriage into position opposite the guide rails of the printing table to shift said carriage from said magazine to the printing position and to return the same to the magazine.

5. A screen printing machine as defined in claim 4 in which the interengaging coupling means on the carriages and reciprocating carrier comprises a projection on one and a vertical slot provided on the other.

CLEMENS ANTON HEINTGES.
